UNITED STATES PATENT OFFICE.

EDWARD WOLFSTEIN, OF NEW YORK, N. Y., ASSIGNOR TO AMERICAN THERMO-WARE COMPANY, OF NEW YORK, N. Y., A CORPORATION OF NEW YORK.

DESIGN FOR A BAROMETER-CASE.

No. 37,919.

Specification for Design.

Patented March 27, 1906.

Application filed February 12, 1906. Serial No. 300,808. Term of patent 7 years.

To all whom it may concern:

Be it known that I, EDWARD WOLFSTEIN, a citizen of the United States, and a resident of the borough of Manhattan, in the city and State of New York, have invented a new, original, and ornamental Design for a Barometer-Case, reference being had to the accompanying drawing, forming a part thereof.

My new, original, and ornamental design

for a barometer-case is shown in perspective in the accompanying drawing.

I claim—

The ornamental design for a barometer-case, as shown.

EDWARD WOLFSTEIN.
